UNITED STATES PATENT OFFICE.

DE WITT E. TALLMADGE, OF SOUTH NORWALK, CONNECTICUT.

INTERNAL-COMBUSTION ENGINE.

1,191,366.

Specification of Letters Patent. Patented July 18, 1916.

Application filed November 6, 1915. Serial No. 60,117.

To all whom it may concern:

Be it known that I, DE WITT E. TALLMADGE, a citizen of the United States, residing at South Norwalk, county of Fairfield, 5 State of Connecticut, have invented an Improvement in Internal-Combustion Engines, of which the following is a specification.

This invention relates to internal combustion engines and consists in certain constructions, and in certain parts, improvements 10 and combinations that will be hereinafter described and then specifically pointed out in the claims hereunto appended.

In the accompanying drawings forming a 15 part of this specification, Figure 1 is a longitudinal section of my novel engine with certain of the parts in elevation; Fig. 2 an elevation as seen from the right in Fig. 1, with the face plate of the casing removed; 20 Fig. 2^a a detail sectional view on the line indicated by 2^a in Fig. 2; Fig. 2^b a detail sectional view on the line indicated by 2^b in Fig. 2, the parts however being in a position corresponding with Fig. 4; Fig. 3 a transverse section on the line 3—3 in Fig. 1, showing a position of the primary and secondary 25 pistons during an intake, and Fig. 4 is a section on the same line, showing a position of the primary and secondary pistons at the 30 instant of an explosion. The position of the parts corresponds in Figs. 1, 2, 2^a and 3.

10 denotes the casing which is shown as made in three parts, 11 the shaft, which is journaled in the ends of the casing, 12 a flywheel carried by the shaft, and 13 the piston chamber which is circular. Within this chamber are three radial equi-distant primary pistons, indicated by 14, each of which carries at each end a rearwardly extending 35 end wall 15, the edge of which fits the outer wall of the piston chamber closely. These end walls may taper outward, as shown in Fig. 1. The primary pistons are carried by segments of a hub indicated as a whole by 40 17. These hub segments are secured to the shaft by tapering keys 18, the ends of which extend into a circular recess 19 in a hub 20 rigidly secured to the shaft. Within the 45 recess is a disk 21 which is forced against the ends of the keys by a relatively strong spring 22 having its other bearing on the base of the recess. The action of the spring pressed disk is to force the keys forward and raise 50

the hub segments so that the edges of the pistons and the end walls will be held 55 closely in engagement with the wall of the piston chamber and make tight joints.

23 denotes the intake for the explosive mixture, 24 the spark plug and 25 and 26 exhaust openings in the piston chamber. 60

27 denotes secondary pistons which, lie within the end walls 15 of the primary pistons. These secondary pistons are concave upon their inner edges to engage the hub formed by the three hub segments and convex upon their outer edges to engage the wall of the piston chamber. The secondary as well as the primary pistons are forced outward into close engagement with the wall of the piston chamber by the tapering keys. 70 It will be noted that the primary pistons and their end walls, in connection with the secondary piston, form, within the piston chamber, three independent chambers which I will term combustion chambers. The combustion chambers are not indicated by reference numerals, however, as their area and position is constantly changing. 75

30 denotes a ring-shaped chamber in the casing, having an opening 31 entirely 80 around it. Centrally located in this chamber is a ring 32 carried by a spider 33, itself rigidly secured to the shaft.

34 denotes hubs mounted upon the ring and adapted to move spirally thereon, as will be more fully explained. Each hub is provided with a circumferential groove 35 to receive a circular bearing 36 in which the hub rotates. Each bearing is carried by an arm 37, the other end of which is rigidly secured to one of the secondary pistons. 90

38 denotes a spiral groove in the wall of the ring-shaped chamber, said groove being interrupted by opening 31.

39 denotes a spiral groove in the periphery 95 of ring 32, which is interrupted at the points of attachment of the ring to the arms of the spider.

40 denotes double-ended pins, two of which are socketed in each hub, on opposite 100 sides thereof, and which are adapted to engage both the groove in the wall of the chamber and the groove in the ring to impart forward movement to the hub and the corresponding secondary piston at a speed in 105 acceleration of that of the primary pistons

and shaft. Each pin is provided with a shoulder, and a spring 41, bearing against the shoulder and the base of the socket in which the pin is seated, acts to force the pin outward, that is toward the wall of the chamber. Each pin is also provided with a stop pin 42 engaging a slot 43 in the hub, which acts to limit the outward movement of the pin when it passes into opening 31 in the wall of the chamber. At approximately opposite points in the wall of the ring-shaped chamber, spiral groove 38 is provided with deepened portions 44, both terminating in inclines 47 and one of which must be provided with a rear shoulder 45 (see Fig. 2^b). When a pin is forced into one of these deepened portions, or into opening 31, by its spring, it passes entirely out of engagement with groove 39 in the ring, as clearly shown in Figs. 2^a and 2^b. There are two conditions that must be distinguished from each other,—when a hub is moving, and when its movement is to be stopped. As has been stated, each time a pin passes opening 31, it must pass out of engagement with the groove in the ring. Under the first condition this is an idle movement and no result follows, as each hub carries two pins, one of which remains in engagement with the grooves in the chamber wall and the ring. When, however, a secondary piston reaches the position shown at the right in Fig. 4, and the corresponding hub is in the position shown in Fig. 2^b, one of the pins in said hub will pass into the recess 44, shown in Fig. 2^b, and will lie in engagement with shoulder 45, and the other pin in said hub will pass into opening 31 which leaves the hub disconnected from the ring, itself carried by the shaft. This stops the movement of the hub and leaves the secondary piston stationary in the position shown at the right in Fig. 4, as will be more fully explained. Means must be provided for disengaging the pins from these deepened portions, starting the hubs forward and engaging the pins again with groove 39. This is effected by the engagement of the primary pistons with arms 37, carried by the secondary pistons. In order to insure a yielding engagement of the primary pistons with the arms, I provide bumpers 46 upon the primary pistons, which take up the shocks of the blows, and start the secondary pistons forward. These bumpers may be shells closed at their outer ends, the inner ends of the shells, and the springs by which they are forced outward, being socketed in the primary pistons.

60 The operation is as follows: Whenever a combustion chamber passes the intake, as in Fig. 3, the explosive mixture will pass into said chamber. The primary pistons, and with them the shaft and ring 32, rotate continuously. When the pins in a hub are in

engagement with the grooves in the wall of the chamber and the ring, the hub and the secondary piston connected therewith by an arm 37 will be carried forward at an accelerated speed, that is at greater speed 70 than that of the primary pistons. This causes compression of the mixture in a combustion chamber. Compression continues in the combustion chamber that has just taken mixture until the parts reach the position 75 shown in Fig. 4. At this instant, one of the pins 40 in the corresponding hub 34 will drop into one of the depressed portions 44 of groove 38 (see Fig. 2^b) and the other pin in the same hub will pass out of the groove 80 owing to its interruption by opening 31. This will stop the forward movement of the hub and consequently of the secondary piston to which the hub is connected. The combustion chamber in which compression has 85 taken place will now be at the spark plug and the explosion takes place, the engagement of pin 40 with shoulder 45 (see Fig. 2^b) preventing backward movement of the secondary piston. The effect is to drive the 90 primary pistons and the shaft forward. The secondary piston that has been stopped by the engagement of a pin with a shoulder 45 remains stationary until it is started forward by the engagement of the bumper on 95 the following primary piston with the arm 37 of the stationary secondary piston. After the explosion, the combustion chamber is expanded by the forward movement of the primary piston and is then contracted again 100 by the forward movement of the following secondary piston which is started by the following primary piston. The primary piston forces the secondary piston forward with it until the pins in the corresponding hub 105 again engage the grooves in the wall of the ring-shaped chamber and the ring. As soon as this engagement takes place, the accelerated movement of the secondary piston commences, the effect of which is to partially exhaust the products of combustion through exhaust opening 25, the exhaust being completed at exhaust opening 26. An instant after passing opening 26, the combustion chamber approaching the intake is 110 at its greatest contraction, corresponding in area with the combustion chamber at the right in Fig. 4. In this position, the pins in the corresponding hub 34 will drop respectively into a depressed portion 44 of the 115 groove 38 and into opening 31, and will stop the forward movement of the hub and the secondary piston. An instant later, the primary piston has passed the intake and explosive mixture will pass into the combustion chamber. The secondary piston is then moved forward by the following primary piston and an instant later its accelerated movement, caused by reengagement of the 120 pins with the grooves, commences and com- 125 130

pression takes place in the chamber that has just taken explosive mixture. These operations are continuously repeated in use.

Having thus described my invention, I

5 claim:—

1. An internal combustion engine comprising a shaft, a non-rotating piston chamber, primary pistons secured to the shaft and having rearwardly extending end walls, and forming with the primary pistons and end walls combustion chambers, tapering keys engaging the hub segments and the shaft, a spring pressed disk engaging the keys, for the purpose set forth, a 70 hub 20 secured to the shaft in which the disk and spring are socketed, and means for imparting accelerated movement to the secondary piston.
2. An internal combustion engine comprising a shaft, a piston chamber, primary pistons secured to the shaft and having rearwardly extending end walls, secondary pistons mounted on the shaft independently of the primary pistons and forming with said pistons and end walls combustion chambers, and means for imparting accelerated movement to the secondary pistons to produce compression and exhaustion in the combustion chamber.
3. An internal combustion engine comprising a shaft, a piston chamber, primary pistons secured to the shaft and having rearwardly extending end walls, secondary pistons mounted on the shaft independently of the primary pistons, and forming with said pistons and end walls combustion chambers, a spirally grooved ring-shaped chamber having an opening around it, a spirally grooved ring centrally located in said chamber and carried by the shaft, hubs mounted upon the ring and having spring controlled pins adapted to engage the grooves in the chamber and the ring and having circumferential grooves, bearings in the circumferential grooves in which the hubs rotate, and arms connecting said bearings with the secondary pistons.
4. An internal combustion engine comprising a shaft, a piston chamber, primary pistons secured to the shaft and having rearwardly extending end walls and hub segments, together forming a hub, secondary pistons mounted to have rotary movement on said hub and forming with the primary pistons and end walls combustion chambers, and means for imparting accelerated movement to the secondary pistons, for the purpose set forth.
5. An internal combustion engine comprising a shaft, a piston chamber, primary pistons having rearwardly extending end walls and hub segments, together forming a hub, secondary pistons mounted to have rotary movement on said hub, and forming with the primary pistons and end walls combustion chambers, spring pressed tapering keys for securing the hub segments to the shaft and for forcing the primary and secondary pistons outward against the wall of the chamber, and means for imparting accelerated movement to the secondary pistons, for the purpose set forth.
6. An internal combustion engine comprising a shaft, a piston chamber, primary pistons having rearwardly extending end walls and hub segments, together forming a hub, secondary pistons mounted to have rotary movement on said hub, and forming with the primary pistons and end walls combustion chambers, and means for imparting accelerated movement to the secondary pistons.
7. An internal combustion engine, a 75 shaft, primary pistons secured thereto, secondary pistons mounted on the shaft independently of the primary pistons, a spirally grooved ring-shaped chamber having a circular opening, a spirally grooved ring in 80 said chamber carried by the shaft, hubs mounted upon the ring and having spring controlled pins adapted to engage the grooves in the chamber and the ring, bearings in which the hubs rotate, and arms 85 connecting said bearings to the secondary pistons, whereby accelerated movement is imparted to said secondary pistons.
8. An internal combustion engine, a 90 shaft, primary pistons secured thereto, secondary pistons mounted on the shaft independently of the primary pistons, a ring-shaped chamber having a spiral groove provided with deepened portions and having a circular opening, a spirally grooved 95 ring in said chamber carried by the shaft, hubs mounted upon the ring, spring controlled pins in the hubs adapted to engage the grooves in the chamber and the ring, bearings in which the hubs rotate and arms 100 connecting the bearings to the secondary pistons, the engagement of the pins with the grooves causing accelerated movement of the hubs and secondary pistons, and passing of the pins in a hub into one of the depressions and the circular opening respectively, disengaging the pins from the ring and stopping the movement of the hubs and the secondary pistons.
9. An internal combustion engine, a 105 shaft, primary pistons secured thereto, secondary pistons mounted on the shaft independently of the primary pistons, a ring-shaped chamber having a circular opening and a spiral groove provided with deepened 115 portions, one of which has a rear shoulder, for the purpose set forth, a spirally grooved ring in said chamber carried by the shaft, hubs mounted upon the ring, spring controlled pins in the hub adapted to engage 120 the grooves in the chamber and the ring, bearings in which the hubs rotate, and arms connecting the bearings to the secondary pistons.
10. An internal combustion engine, a 125 shaft, primary pistons secured thereto, secondary pistons mounted on the shaft independently of the primary pistons, a ring-shaped chamber having a spiral groove provided with deepened portions terminating 130

- in inclines and having a circular opening, a spirally grooved ring in said chamber carried by the shaft, hubs mounted upon the ring, spring controlled pins in the hubs adapted to engage the grooves in the chamber and the ring, bearings in which the hubs rotate, arms connecting the bearings to the secondary pistons, passing of the pins into a depression and the circular opening stopping the movement of the hubs and the secondary pistons, and means for causing reengagement of the pins with the grooves.
10. In an internal combustion engine, a shaft, primary pistons secured thereto and provided with bumpers, secondary pistons mounted on the shaft independently of the primary pistons, a ring-shaped chamber having a spiral groove provided with deepened portions terminating in inclines and having a circular opening, a spirally grooved ring in said chamber carried by the shaft, hubs mounted upon the ring, spring controlled pins in the hubs adapted to engage the grooves in the chamber and the ring, bearings in which the hubs rotate, and arms connecting the bearings to the secondary pistons, passing of the pins into a depression and the circular opening respectively, stopping the movement of the hubs and the secondary pistons and engagement of the bumpers with the arms starting the secondary pistons and hubs forward and causing reengagement of the pins with the grooves.
11. In an internal combustion engine, a shaft, primary pistons secured thereto, secondary pistons mounted on the shaft independently of the primary pistons, a ring-shaped chamber having a spiral groove provided with deepened portions and having a circular opening, a spirally grooved ring in said chamber carried by the shaft, hubs mounted upon the ring, spring controlled pins in the hubs adapted to engage said grooves, bearings in which the hubs rotate and arms connecting the bearings to the secondary pistons, passing of the pins into a depression and the circular opening stopping movement of the hubs and the secondary pistons, and engagement of the primary pistons with the arms starting the secondary pistons forward and causing reengagement of the pins with the grooves.
12. In an internal combustion engine, a shaft, primary pistons secured thereto, secondary pistons mounted on the shaft independently of the primary pistons, a ring-shaped chamber having a spiral groove provided with deepened portions and having a circular opening, a spirally grooved ring in said chamber, a spider secured to the shaft and having arms passing through the opening by which the ring is carried, hubs mounted upon the ring, spring controlled pins in the hubs adapted to engage said grooves, bearings in which the hubs rotate,

and arms also passing through the opening which connect the hubs to the secondary pistons.

13. In an internal combustion engine, a shaft, primary pistons secured thereto, secondary pistons mounted on the shaft independently of the primary pistons, a ring-shaped chamber having a spiral groove provided with deepened portions and having a circular opening, a spirally grooved ring in said chamber carried by the shaft, hubs mounted upon the ring, shouldered pins socketed in the hubs and adapted to engage said grooves, springs acting to force said pins outward, stop pins which limit the outward movement of the pins, bearings in which the hubs rotate and arms connecting the bearings with the secondary pistons.

14. In an internal combustion engine, a piston chamber having an intake, a spark plug and exhaust openings, a shaft, primary pistons carried thereby and having rearwardly extending end walls, secondary pistons mounted on the shaft independently of the primary pistons and forming with said pistons and end walls combustion chambers, and means operated by the shaft for accelerating the movement of the secondary pistons to produce compression in the combustion chambers before an explosion and exhaustion in said chambers after an explosion.

15. In an internal combustion engine, a piston chamber having an intake, a spark plug and exhaust openings, a shaft, primary pistons carried thereby and having rearwardly extending end walls, secondary pistons mounted on the shaft independently of the primary pistons and forming with said pistons and end walls combustion chambers, a spirally grooved ring-shaped chamber having a circular opening, a spirally grooved ring in said chamber carried by the shaft, hubs mounted upon the ring and having spring controlled pins adapted to engage said grooves, bearings in which the hubs rotate, and arms connecting said pins to the secondary pistons.

16. In an internal combustion engine, a piston chamber having an intake, a spark plug and exhaust openings, a shaft, primary pistons carried thereby and having rearwardly extending end walls, secondary pistons mounted on the shaft independently of the primary pistons and forming with said pistons and end walls combustion chambers, a ring-shaped chamber having a spiral groove provided with depressions and having a circular opening, a spirally grooved ring in said chamber carried by the shaft, hubs mounted upon the ring, spring controlled pins in the hubs adapted to engage said grooves, bearings in which the hubs rotate, and arms connecting said bearings to the secondary pistons.

17. In an internal combustion engine, a

piston chamber having an intake, a spark plug and exhaust openings, a shaft, primary pistons carried thereby and having rearwardly extending end walls, secondary pistons mounted on the shaft independently of the primary pistons and forming with said pistons and end walls combustion chambers, a spirally grooved ring-shaped chamber having a circular opening, oppositely located depressions in the groove, one of which is provided with a shoulder, for the purpose set forth, a spirally grooved ring in said chamber carried by the shaft, hubs mounted upon the ring and having spring controlled pins adapted to engage said grooves, bearings in which the hubs rotate, and arms connecting said bearings to the secondary pistons. 15

In testimony whereof I affix my signature.

DE WITT E. TALLMADGE.
